UNITED STATES PATENT OFFICE.

WILLIAM HUNTER, OF KINCARDINE, CANADA.

METALLIC PILING.

No. 819,067.

Specification of Letters Patent.

Patented May 1, 1906.

Application filed April 7, 1905. Serial No. 254,423.

To all whom it may concern:

Be it known that I, WILLIAM HUNTER, bookkeeper, of the town of Kincardine, in the county of Bruce, Province of Ontario, Canada, have invented certain new and useful Improvements in Metallic Piling, of which the following is a specification.

My invention relates to improvements in metallic piling; and the object of the invention is to provide a very cheap, strong, and durable metallic pile which will be absolutely water-tight; and it consists, essentially, of a series of metallic pillars composed of U-beams forming two sides of the pillar and vertically disposed and with inwardly-extending opposite flanges, a vertical connecting-beam connecting the side beams, an I-beam extending vertically between the pillars and between the opposing flanges of the side beams of the pillar and having the flanges thereof extending inside the flanges of the side beams, and angle-bars arranged to hold the flanges of the I-beam against the flanges of the side bars of the pillar, and a filling of cement for the pillars, all the parts being arranged and constructed in detail as hereinafter more particularly explained.

Figure 1 is a view of a portion of my metallic piling. Fig. 2 is an enlarged sectional plan view of my metallic pillar and connecting-beams. Fig. 3 is a similar view to Fig. 2, showing an alternative construction.

In the drawings like characters of reference indicate corresponding parts in each figure.

35 A represents my metallic pillars comprising the vertically-disposed side beams A' A', having the flanges A² A² thereof extending inwardly into close proximity to the flanges A³ A³ of the opposing beam.

40 A⁴ is a vertically-disposed I-beam secured to the side beams by rivets 2 and connecting the side beams A' A' together.

B represents I-beams extending between the pillars from pillar to pillar and between the inwardly-extending opposing flanges A² A² of the side bars of the pillar. The flanges B' of the I-beam B extend to the inside of the flanges A² and A³ of the pillar and are held against the inside surface of such flanges

50 by vertical angle-bars B', secured to the I-beams B by rivets 3. The pillars A are provided with a suitable filling C, of cement or other material. By this means the joint between the pillars and the connecting I-beams

55 are made absolutely water-tight.

In Fig. 3 I show the securing angle-bars

B² secured to the interior surface of the side bars A' of the pillars A, so as to grip the flanges of the I-beam between the inwardly-extending flange of the angle-bar and the inwardly-extending flange of the side beam of the pillar.

From this description it will be seen that I have provided a very simple, cheap, and easily-constructed metallic piling which will be perfectly water-tight.

What I claim as my invention is—

1. A metallic piling comprising vertical opposing beams having inwardly-extending opposing flanges, connecting means between the opposing beams, a vertically-disposed I-beam connecting the adjacent pillars and means without said opposing flanges of said opposing beams for securing the flanges of the I-beam within the same, substantially as described.

2. A metallic piling, comprising vertical opposing beams forming pillars and having inwardly-extending opposing flanges, connecting means between the opposing beams, a vertically-disposed I-beam connecting the adjacent pillars having the flanges thereof extending within the opposing flanges of the opposing beams and angle-bars without said opposing flanges designed to hold the flanges of the I-beams and the flanges of the opposing beams together as and for the purpose specified.

3. A metallic piling, comprising vertical opposing beams forming pillars and having inwardly-extending opposing flanges, connecting means between the opposing beams, vertically-disposed I-beams connecting the adjacent pillars having the flanges thereof extending within the opposing flanges of the opposing beams, and angle-bars secured to the I-beams and designed to hold the flanges of the I-beam and the opposing flanges of the opposing beams together as and for the purpose specified.

4. A metallic piling, comprising vertical opposing beams forming pillars and having inwardly-extending opposing flanges, vertically-disposed I-beams connecting the adjacent pillars, and angle-irons adapted to hold the flanges of said I-beams against the opposing flanges of said vertical opposing beams, substantially as described.

WM. HUNTER.
